His Attorney.

UNITED STATES PATENT OFFICE.

HUGH D. SANBORN, OF SWAMPSOFT, MASSACHUSETTS, ASSIGNOR TO GENERAL ELECTRIC COMPANY, A CORPORATION OF NEW YORK.

CONSTANT-CURRENT REGULATOR.

1,313,117.

Specification of Letters Patent. Patented Aug. 12, 1919.

Application filed November 5, 1917. Serial No. 200,406.

To all whom it may concern:

Be it known that I, HUGH D. SANBORN, a citizen of the United States, residing at Swampscott, in the county of Essex, State 5 of Massachusetts, have invented certain new and useful Improvements in Constant-Current Regulators, of which the following is a specification.

My invention relates to constant current 10 regulating devices of the type represented by movable coil constant current transformers, variable series reactances somewhat resembling in appearance such constant current transformers, and variable reactances 15 comprising relatively movable cores and coils which are more or less drawn together or separated as the current tends to change. An object of my invention is to provide such devices with means for moving their parts 20 to low voltage (or great reactance) positions whenever they cease to supply their loads, as when electric circuits thereof are opened. By these means the devices are automatically brought to such positions when 25 the loads are materially reduced, that when they are next started the devices and the circuits attached to them are protected against unduly high currents.

In carrying out my invention I employ 30 means, preferably weights, to move the movable parts of the devices to low voltage positions whenever the loads are materially reduced, and to hold the parts in these positions until the loads are resumed. The regulating devices are relieved of the effects of 35 these means (as the pulls of the weights) during the normal operations of the regulating devices. Preferably electric motors energized by auxiliary windings on the regulating devices raise the auxiliary weights 40 when their effects are to be dispensed with.

In the accompanying drawings and the 45 following description I have shown and described in some detail the best embodiment of my invention in constant current transformers that I am now aware of. I contemplate that my invention will find its greatest use in connection with constant current transformers, but it will be understood that 50 my invention is not limited to the specific embodiment here illustrated and described, nor even to transformers. The single figure of the drawing illustrates in elevation and more or less diagrammatically, a constant

current transformer embodying my invention.

The constant current transformer illustrated is, by itself, substantially of a very common form. The core 1 is of the three legged type, the windings surrounding the middle leg thereof. The usual windings of this particular form of transformer comprise a winding 2 (which I shall hereafter regard as the primary winding) fixed with respect to the core and a winding 3 (hereafter regarded as the secondary winding) movable with respect to the core and with respect to the fixed winding 2. It will be understood that my invention is not limited however to a device in which there is a fixed primary and movable secondary winding, or to a device of a plurality of windings, or a device in which but one winding is movable. The movable winding 3 is suspended by cords or other flexible members 4, from one end of the lever 5 which is pivoted midway its ends. From the other end of the lever 5 is suspended the usual counterbalancing weight 8 by means of another cord or flexible member 9. As devices are connected to or disconnected from the secondary winding, and the current in the secondary winding thereupon tends to change, the movable winding 3 moves toward or away from the fixed winding 2 and assumes such a new position in each instance that the current delivered by the secondary winding is of a substantially constant value (within the range of the apparatus) irrespective of the number of devices connected to the secondary winding. The movement of the movable winding is a result of the magnetic repulsion between the two windings. The construction and normal operation of such constant current transformers is very well-known and need be no further described.

Such a constant current transformer endeavors under all conditions to maintain a constant value of current in its secondary winding. Hence if either the primary circuit or the secondary circuit is opened, or if the voltage on the primary winding otherwise falls below a given value, then the movable winding moves as close as possible to the fixed winding, that is to its highest voltage position. To state this more generally, whenever the transformer ceases to supply its load, the movable winding is

moved to its highest voltage position. Consequently when the interrupted circuit is again closed (there being a number of translating devices ready to receive current), or 5 to state it more generally when the load is abruptly resumed, both the transformer itself and the translating devices connected thereto are subjected to unduly high currents until the movable winding can find its 10 proper position. My invention provides means for eliminating this undesirable feature which is found not only in constant current transformers but also in other constant current regulating devices of the type to 15 which my invention applies. The means I have illustrated in the drawing comprises a weight 12, which here may be called the auxiliary weight, the effect of which is added to the effect of the weight 8 whenever 20 the transformer ceases to supply its load in the normal fashion. The auxiliary weight 12 is normally carried by the cord or other flexible member 13, and near its center is provided with a vertical passage 25 through which the cord 9 passes freely. During the normal operation of the regulating device the auxiliary weight 12 is held above the upper end of the path of travel of the counterbalancing weight 8; hence 30 with the auxiliary weight 12 in its suspended position, it has no effect on the operation of the transformer. The cord 13 is carried by the drum 14 which by means of gears 15 is coupled with the electric motor 35 16. This electric motor is supplied with energy by the auxiliary winding 20, in effect a secondary winding, placed on the middle leg of the core 1 adjacent the primary winding 2. The connections 21 between the winding 20 and the motor 16 include a resistance member 22 in shunt to which is provided the switch 23. This switch 23 is biased to a closed position by means of the spring 24; a movable part of the switch 23 is located 40 45 within the range of travel of the auxiliary weight 12, this weight 12 when near the upper end of its travel and under the influence of the motor 16 engaging the movable member of the switch 23 to open this switch 50 and hence to open the short circuit about the resistance 22. When the switch 23 is closed and normal voltage is impressed on the primary winding 2, the auxiliary winding 20 supplies sufficient energy to rotate 55 motor 16 and raise the auxiliary weight 12. The resistance 22 is, however, of such value that when the switch 23 is open and hence the resistance 22 effective, the motor 16 can receive substantially only sufficient energy to 60 hold it against backward rotation under the pull of the weight 12; in other words, with the resistance 22 in circuit the motor 16 can receive from the auxiliary winding 20 substantially only sufficient energy to lock the 65 motor against the pull of the weight 12.

A stop 26 attached to the core 1 limits the elevation of the auxiliary weight 12 in case the resistance 22 is of insufficient value to altogether stop the motor. In series with the secondary circuit is a relay or switch 27 70 which under the influence of gravity normally tends to open its contacts 28. These contacts 28 are connected in the circuit between the motor terminals and the winding 20 as illustrated. Under the action of current in the secondary winding, the armature of the relay 27 is held in an elevated position with its contacts 28 bridged and the circuit between the motor 16 and winding 20 closed thereat. The value of the current necessary to raise the armature of the relay 27 will be understood from the following 75 description of the operation of my invention. 80

The operation of this device is as follows: 85 Before any energy is supplied to the primary winding of the regulating device, the motor 16 is without energy, the auxiliary weight 12 rests upon the weight 8 in their lowermost positions, the switch 23 is closed, 90 the circuit between the motor 16 and the winding 20 is broken at the contacts 28, and the movable winding 3 is held in its uppermost or lowest voltage position by the combined effects of the weights 8 and 12. When 95 thereafter energy is supplied to the primary winding 2, the secondary winding 3 and the devices connected thereto have impressed upon them the minimum voltage and are subjected to the minimum current. The current flowing through the secondary winding 3 and the devices connected thereto raises the armature of the relay 27 and closes the circuit at the contacts 28, and thereupon the motor 16 receives sufficient energy from the auxiliary winding 20 to rotate the drum 14 and raise the auxiliary weight 12 from its position in engagement with the weight 8; the weight 12 continues its upward movement until it engages with the movable part 100 of the switch 23 and opens that switch whereupon the motor is either locked with the weight 12 in its elevated position by reason of the insertion of the resistance 22 in series with the motor 16, or receives such 105 diminished power as to continue the elevation of the weight 12 only into engagement with the stop 26. As the weight 8 and hence the movable winding 3 is relieved of the effects of the weight 12, the movable 110 winding 3 gradually falls until it reaches the proper position as determined by the repulsion of the windings 2 and 3. Hence instead of impressing on the secondary circuit a voltage in excess of the required voltage and subjecting the secondary winding 115 and the devices connected thereto to undue currents (as heretofore), a minimum voltage and current is first impressed on the secondary circuit and then the voltage and cur- 120 125 130

rent are raised to the proper values. So long as the regulating device continues thereafter to supply its load in a proper manner, it operates as though the auxiliary weight 12 and the apparatus controlling the position of this weight were absent. If, however, the secondary circuit is opened at any time, the armature of the relay 27 falls and the contacts 28 and the circuit to the motor 16 are opened; on the other hand should the primary circuit be opened, the auxiliary winding 20 becomes unable to supply energy to the motor 16. Under either of these conditions the motor 16 is unable to sustain the auxiliary weight 12 in its elevated position, and hence the auxiliary weight 12 falls into engagement with the weight 8, and adds its effect thereto and causes the movable winding 3 to return to its elevated or lowest voltage position.

While I have described the principle of my invention and the best mode I have contemplated for applying this principle, other modifications will occur to those skilled in the art and I aim in the appended claims to cover all modifications which do not involve a departure from the spirit and scope of my invention.

What I claim as new and desire to secure by Letters Patent of the United States, is:—

1. The combination with a constant current regulating device comprising a movable member and means tending to move said movable member to its lowest voltage position, of means for augmenting the effect of the first mentioned means when the regulating device ceases to supply its load.

2. The combination with a constant current regulating device comprising a movable member, of means for moving said movable member to a low voltage position and means for relieving said regulating device from the effect of the first mentioned means during the normal operation of said regulating device and applying the said first mentioned means thereto when the regulating device ceases to supply its load.

3. The combination with a constant current regulating device comprising a movable member, of an auxiliary winding inductively related to a winding of said regulating device, a weight for moving said movable member to a low voltage position, an

electric motor connected to said auxiliary winding for relieving said regulating device from the pull of said weight, and a switch, said switch being actuated by said weight to stop the motor when the weight is near the end of its travel under the influence of said motor.

4. The combination with a constant current regulating device comprising a movable member and a weight partially counterbalancing said movable member, of an auxiliary weight for augmenting the pull of the first mentioned weight, and means for raising said auxiliary weight from the path of travel of said first mentioned weight during the normal operation of the regulating device and allowing the auxiliary weight to rest upon the first mentioned weight when the regulating device ceases to supply its load.

5. The combination with a constant current regulating device comprising a movable member, of a weight for moving said movable member to a low voltage position, an electric motor for relieving said regulating device from the pull of said weight, a switch for stopping said motor when acted on by said weight, and a stop for said weight, both said switch and said stop being near the end of the path of travel of said weight when said auxiliary weight is acted on by said motor.

6. The combination with a constant current regulating device comprising a movable member, of an auxiliary winding inductively related to a winding of said regulating device, a weight for moving said movable member to a low voltage position, an electric motor connected to said auxiliary winding for relieving said regulating device from the pull of said weight, a resistance in series between said motor and said auxiliary winding, and a switch for short circuiting said resistance, said switch being acted on by said weight near the end of its travel under the influence of said motor to open the short circuit and said resistance being of substantially sufficient value to substantially prevent the motor rotating.

In witness whereof, I have hereunto set my hand this 31st day of October, 1917.

HUGH D. SANBORN.
